UNITED STATES PATENT OFFICE.

ERICK N. KINDLAND, OF JAMESTOWN, NEW YORK.

JAR TOP.

Application filed May 13, 1921. Serial No. 469,273.

To all whom it may concern:

Be it known that I, ERICK N. KINDLAND, a citizen of the United States, residing at the city of Jamestown, in the county of Chautauqua and State of New York, have invented certain new and useful Improvements in Jar Tops, of which the following, taken in connection with the accompanying drawings, is a specification.

10 The invention relates to preserving or packing containers; and the object of the improvement is to provide a preserving jar with a top or cap which can be quickly and easily opened to pour forth the contents 15 without the removal of said top, and as quickly closed, at the same time making use of a binding member by means of which said top can be rigidly clamped in position for preserving the contents, provision being also 20 made so that said top can be turned as a whole to one side without dismemberment of the same; and the invention consists in the novel features and combinations hereinafter set forth and claimed.

25 In the drawings, Figure 1 is a perspective view of the jar with the top in the open position; and Fig. 2 is a vertical diametrical sectional view of the jar and top alongside the binding bail showing the parts in the open 30 position. Fig. 3 is a sectional view of the jar top at right angles to the view shown in Fig. 2 showing a modification of the jar top with the parts in the closed position.

Fig. 4 is a top plan view of the jar top with 35 the parts in the closed position. Fig. 5 is a detailed plan view of the main portion of the jar top or cap showing the construction and arrangement of the same; and Fig. 6 is a similar view of the lesser portion of 40 the jar cap. Fig. 7 is a detailed plan view of the attaching clip on the wire binding bail. Fig. 8 is a sectional view of the central portion of the double cap showing the central downward depression therein and 45 a modification of the bail depressed to rotatively fit within the same without the use of a clip.

Like characters of reference refer to corresponding parts in the several views.

50 The numeral 10 designates the jar which is preferably made of glass, though it may

be made of metal, which jar 10 has the jar cap binding bail 11 attached by means of the leverage bail 12 and wire 13 around the neck of the jar 10.

55

The attaching wire 13 is preferably provided with the holding clips 14 at each side into which the ends of the leverage bail 12 extend so as to pivotally mount said leverage bail with a downwardly projecting return bend leverage loop 17 into which the in-turned ends 16 of the binding bail 11 are pivotally and removably inserted, the spring of the wire bail 11 being sufficient to permit the removal of said end 16 from the wire 60 loops 17.

The binding bail 11 has the binding clip 18 slipped thereon through the holes 19. The clip 18 has the downwardly projecting boss 20, and the holes 19 are preferably sufficiently 70 large to permit the clip 18 being slipped onto the turned ends 16 of the bail 11 to thereby removably assemble the parts.

The jar top or cap consists of the main cap portion 21 which has the large exit opening 22 for the contents, and small air inlet opening 23 therethrough and the notch 24 in the side which fits over a lug 25 on the rim of the jar 10 to prevent said cap part 21 from turning. A second and smaller cap or disk 75 portion 26 fits over the central portion of the cap part 21. Both of the cap parts 21 and 26 have a central depression 27 so that the smaller top portion 26 rotatively fits 80 into the depression in the larger top portion 21 and receives the boss 20 on the binding clip 18. Said boss 20 and the depression 27 are round so that the cap portion 26 may be rotatively turned by means of the up-turned lug 28 to thereby bring the holes 22 90 and 23 or 33 in each of the portions 21 and 26 into alignment so that the contents of the jar 10 can be poured through the larger exit 22, the hole 23 acting as an air inlet.

The arrangement of the hole 22 is for 95 liquids or powdered materials, which may be poured through said exit 22. The holes 33 in the disk portion permit sprinkling powders and liquids therethrough. Most kinds of preserved fruit necessitates the removal of 100 the entire cap, but many sauces and powdered substances which it is desirable to

preserve in an air-tight can or jar permit of being poured through such an opening as 22, the arrangement of the jar cap permitting the quick closure of the holes 22 and 23 to 5 preserve the contents of the jar.

The joint around the outer edge of the cap portion 21 may be sealed with a rubber packing ring 29. For substances which it is not necessary to keep in an air-tight container, said rubber packing ring may be dispensed with.

It is obvious that the jar top as shown in Figs. 1 and 2 will be removable in different parts, particularly as to the cap portions 21 and 26 when the bail is removed therefrom. 15 This is necessary for cleansing the same, but for use with certain substances, it is preferable to unite the portions of the top. This is preferably accomplished by means of a 20 screw bolt 30 which extends through the cap portions 21 and 26 and the binding clip 18, the head of the bolt 30 preferably having a notch in the center thereof to receive a downward bend 32 in the binding wire 11, 25 and a thumb nut 31 on the threaded inner end of the bolt 30 on the inner side of the cap to thereby firmly unite all the parts of the cap or top and permit said cap to be turned to one side as an entirety and 30 turned to position by the release of the bails 11 and 15.

The removable clip 18 is preferred for most uses, though the modified form shown in Fig. 8 might be used for certain purposes. 35 The binding effect, however, is not as good as with said clip 18. For substances with which the packing ring 29 is omitted, it is apparent that the cap 21 would be easily rotatable on the smooth jar top. Accordingly, 40 the arrangement of the lug 25 and notch 24 is necessitated, thereby preventing all rotation of said cap.

What is claimed as new is:

1. A jar having an upward projection on 45 the rim thereof, a cover having a notched opening therein fitting over said projection to prevent the rotation of said cover, a disk-shaped portion rotatably mounted upon said cover, said cover and disk-shaped portion having openings therethrough registerable 50 with one another to pour out the contents, a sunken portion central of said cover and disk-shaped portion, a leverage wire pivotally attached to a wire around the neck 55 of said jar, a binding wire pivotally attached by its opposite inturned ends in loops in said leverage wire, a clip slidably and removably mounted on said binding wire having a downward projection to hold said disk-shaped portion on said cover portion with 60 freedom of rotation when the pressure of said binding wire is released, and a projecting lug on said disk-shaped portion to strike against said binding wire and limit the rotation of said disk-shaped portion.

2. In combination with a jar, a top including a pair of superimposed members having pouring holes for registry with each other, each of said members having a central circular depression, the depression of 70 the upper member extending into the depression of the lower member so as to rotatably unite the members, a clip seated on the upper member and having a circular depending boss rotatably fitted in the depression 75 of the upper member, and means engaging the clip to exert downward pressure thereon to secure the top in position on the jar and to hold the members against rotation.

3. In combination with a jar, a top including a pair of superimposed members having pouring holes for registry with each other, each of said members having a central circular depression, the depression of 80 the upper member extending into the depression of the lower member so as to rotatably unite the members, and means to secure the top to the jar including a part which is fitted in the depression of the upper 85 member to allow of rotation thereof in one position of said means and in a second position of the latter to press down on the depression of the upper member to secure the latter against rotation.

4. In combination with a jar, a top including a pair of superimposed members having pouring holes for registry with each other, each of said members having a central circular depression, the depression of the upper 90 member extending into the depression of the lower member so as to rotatably unite the members, a clip seated on the upper member and having a circular depending boss rotatably fitted in the depression of the upper 95 member, a bolt extending through the boss and through the depressions and having a nut thereon to connect the parts, and locking means to secure the top to the jar engaged with the clip to force the latter against the 100 members to prevent rotation of the latter.

5. In combination with a jar, a cover for 105 the jar including a pair of superimposed members, the lower of which seats on the jar, engaging means between the jar and 110 said lower member to hold the latter against rotation, means to pivotally connect the members to allow of rotation of the upper member, said members having egress openings movable into and out of registry, locking means for the cover to secure same to the jar, and a handle on the upper member engageable with the locking means to limit the extent of rotation of the upper member.

6. In combination with a jar, a cover for 115 the jar including a pair of superimposed members, the lower of which seats on the jar, a projection on the top of the jar, the 120 lower member having a cut-out receiving the projection, means to rotatably connect 125 the projection, means to rotatably connect 130

the upper member to the lower member, said members having outlet openings movable into and out of registry, means to secure the cover to the jar, and an upwardly extending handle on the upper member engageable with the locking means to limit the extent of rotation of the upper member.

In testimony whereof I have affixed my signature in the presence of two witnesses.

ERICK N. KINDLAND.
